UNITED STATES PATENT OFFICE

2,296,147

MARINE VELOCIPEDE

George F. Cremer, Milwaukee, Wis.

Application November 22, 1940, Serial No. 366,663

2 Claims. (Cl. 115—27)

This invention appertains to boats, and more particularly to boats of the character known as "marine velocipedes," and the same is an improvement over my prior Patent No. 551,367, issued to me December 17, 1895.

In recent years, bicycle-propelled catamarans have again become very popular for lake and amusement resorts, and these catamarans are substantially of the same character as that shown in my above-mentioned patent. Considerable 10 difficulty has been had with the proper assembling of the propeller shafts on the boats relative to the hulls thereof and the drive mechanism.

It is, therefore, one of the primary objects of my present invention to provide a novel means for mounting the propeller shaft on the hulls, whereby the angle of the propeller shaft relative to the hulls can be readily changed to suit varying conditions.

Another object of my invention is the provision of a novel hanger casting for supporting the front end of the propeller shaft and the bearings for the propeller shaft and the drive sprocket shaft, whereby the bearings will be effectively 25 protected from the water.

A further important object of my invention is the provision of an attaching plate for the hanger casting and novel means for forming the plate and hanger casting relative to one another, whereby a rigid connection will be had, and whereby a desired adjustment of the hanger casting on the plate can be obtained by the mere loosening of a single bolt.

A still further object of my invention is the provision of a novel arrangement of steering parts extending from the steering post to the rudder, whereby such parts will be out of the way, and whereby all lost motion will be eliminated.

With these and other objects in view, the invention consists in the novel construction, arrangement, and formation of parts, as will be hereinafter more specifically described, claimed, and illustrated in the accompanying drawings, in which drawings:

Figure 1 is a longitudinal sectional view through my novel catamaran, taken on the line 1—1 of Figure 2, looking in the direction of the arrows.

Figure 2 is a top plan view of my boat.

Figure 3 is an enlarged, fragmentary, detail, sectional view taken on the line 3—3 of Figure 4, looking in the direction of the arrows, illustrating my novel hanger casting and supporting plate therefor.

Figure 4 is a transverse, sectional view through 55

the hanger casting and supporting plate, the view being taken on the line 4—4 of Figure 3, looking in the direction of the arrows.

Figure 5 is a detail, sectional view taken on the line 5—5 of Figure 1, looking in the direction of the arrows, illustrating one of the hanger rods for the propeller shaft.

Figure 6 is a fragmentary, detail, sectional view illustrating one of the adjustable brace rods for the bicycle frame.

Referring to the drawings in detail, wherein similar reference characters designate corresponding parts throughout the several views, the letter B generally indicates my improved boat, and the same includes a pair of spaced, elongated boat hulls 10 and 11. These hulls 10 and 11 can be constructed in any approved manner to form a seaworthy arrangement.

Slotted supporting straps 12 are secured to the upper faces of the hulls 10 and 11, and brace plates 13 and 14 extend across the hulls and are adjustably connected to said straps, as in my above-noted prior patent. These cross frame plates 13 and 14 have rigidly connected thereto a bicycle frame 15, and this frame includes a saddle seat 16 and a steering post 17 provided with handle bars 18. The bicycle frame also rotatably supports the pedal shaft 19 having a drive sprocket wheel 20 keyed or otherwise secured thereto, over which is trained a forwardly extending sprocket chain 21.

The twin hulls 10 and 11 can be braced and connected together at other desired points, and, as shown in the drawings, I can provide a rear cross frame plate 22. The extreme stern ends of the twin hulls 10 and 11 are connected by a supporting structure 23 for the rudder 24. The supporting structure 23 can include a cross bar 25 rigidly connected to the hulls and a substantially U-shaped brace strap 26. The ends of the strap can be riveted or otherwise fastened to the cross bar 25. The rudder shaft 27 is rotatably mounted in bearing openings formed in the bar 25 and the straps 26, and the steering shaft has rigidly connected therewith a steering arm 28.

Between the hulls 10 and 11, I arrange the propeller shaft 29, and the rear end of this shaft has connected therewith a screw propeller 30. The front end of the propeller shaft 29 is supported in a novel manner, and the support for the front end of the propeller shaft includes a hanger casting 31. This hanger casting embodies a transversely extending bearing sleeve 32, having connected therewith by spaced parallel ribs 33, an arcuate supporting plate 34. This plate is

provided intermediate its ends with a longitudinally extending slot 35. Formed on the rear end of the plate is a rearwardly directed, longitudinally extending bearing sleeve 36 arranged at right angles to the front bearing sleeve 32. These sleeves are further joined by a rigid backbone or rib 37, which extends down below said bearing sleeves, and this rib or backbone 37 forms a guard for said bearing sleeves.

The front end of the propeller shaft 29 extends 10 into a hollow shaft section 38 received in the sleeve 36, and this hollow shaft section is rotatably mounted in ball bearings 39 carried by the opposite ends of the sleeve. A grease fitting 40 is carried by the sleeve, so as to facilitate the 15 convenient lubricating of the bearings. The extreme front end of the shaft 29 has keyed or otherwise secured thereto a beveled pinion 41, which is adapted to mesh with a beveled gear 42 keyed or otherwise secured to the sprocket 20 drive shaft 43. The sleeve 32 supports suitable ball bearings 44 for the drive sprocket shaft, and this sleeve can also be provided with a fitting 45 to facilitate the lubrication of said bearings.

The end of the drive shaft remote from the 25 beveled gear 42 has keyed or otherwise secured thereto a sprocket wheel 46, and this sprocket wheel 46 has trained thereabout the front end of the sprocket chain 21.

In connection with the hanger casting 31, I 30 utilize a supporting bracket 47, and this bracket includes a lower wall 48 having a centrally disposed arcuate guide track 49, which slidably receives the arcuate top wall 34 of the hanger casting. It is to be noted that the arcuate guide 49 35 includes side flanges 50, which engage the opposite sides of the hanger casting, so as to effectively prevent lateral shifting movement thereof.

The lower wall 48 of the supporting bracket 47 is firmly bolted, as at 51, to the front cross 40 bar 14, and in order to hold the hanger casting in a preferred adjusted position, a bolt 52 is extended through the cross brace 14, the supporting bracket 47, and the slot 35 in the hanger casting. Obviously, by loosening the nut 53 on the bolt 52, the hanger casting can be shifted or rocked back and forth in the guideway 49 of the bracket 47.

The propeller shaft 29 is further supported at 50 spaced points by depending hanger rods 54 and 55. These hanger rods are adjustably mounted on the cross braces 13 and 22, and the lower ends of the hanger rods have swivelly connected thereto, by means of pivots 56, split bearing collars 57, which encircle bearing sleeves 58 through which the shaft 29 extends.

By this construction, the split collar 57 can be turned on the bearing 58, and the bearing and collar can be swung back and forth on its hanger rod.

Thus, the arrangement of the hanger rods and the hanger casting permits the effective changing of the angle of the propeller shaft to suit varying conditions.

Referring back to the steering mechanism for the rudder 24, it will be noted that the steering post 17 of the bicycle frame 15 rotatably extends through the cross front brace 14 and through a guide opening 59 formed in the supporting bracket 47. The lower end of the post 17 has secured thereto a steering crank arm 60, and this crank arm is operatively connected through the medium of a link 61 with one arm of a bell crank 62. This bell crank is rockably mounted at its angle on a pivot bolt 63 carried by the front cross brace 14. A rearwardly extending steering

rod 64 is operatively connected to the bell crank 62, as is clearly shown in Figure 2, and this rod extends in close proximity and parallel to the hull 10, and through a guideway 65. Adjacent the rear end of the boat B, the steering rod 64 is angled, as at 66, toward the center of the boat, and the extreme rear end of the rod is operatively connected to the steering arm 28 on the steering shaft 27 for the rod. This gives a simple but durable steering mechanism and insures the proper turning of the rudder upon the manipulation of the handle bars 18.

I lay great stress on the construction and arrangement of the hanger casting and the supporting bracket 47, as by employing this arrangement I am enabled to quickly assemble the propeller shaft on the boat.

In order to further brace the bicycle frame 15, I can employ a brace rod 67, and the front end of this brace rod 67 is connected with the front brace frame bar 14. The rear end of the brace rod is threaded and is extended through an eye 68 formed on the hub or bearing sleeve for the pedal crank shaft 19. Nuts 69 are threaded on the rod 67 on each side of the eye 68, and by tightening up on the nuts, the brace rod can be firmly clamped in position, and due to a certain spring in the bicycle frame, and the adjustability of the cross frame bars 13 and 14, the sprocket chain 21 slightly tightened or loosened by proper manipulation of the nut 69.

Changes in details may be made without departing from the spirit or the scope of my invention, but what I claim as new is:

1. In a marine velocipede including a pair of similar hulls, cross braces connecting said hulls together, and a seat, a steering post, and a crank pedal shaft carried by the braces, a propeller shaft arranged between said hulls, a supporting plate rigidly secured to one of the cross braces having a longitudinally extending arcuate guide, a hanger casting including right-angularly extending bearing sleeves and an arcuate guide wall slidably fitted in said guide, means adjustably connecting the arcuate guide wall to said supporting bracket, bearings in said bearing sleeves, the forward end of the propeller shaft being fitted in one bearing sleeve and a drive shaft fitted in the other of said bearing sleeves, means carried by the sleeves for lubricating the bearings, means operatively connecting the drive shaft with the propeller shaft, and means operatively connecting the drive shaft with the pedal crankshaft.

2. In a marine velocipede including a pair of spaced similar hulls, cross braces connecting said hulls together, a seat, a steering post, and a pedal crankshaft carried by certain of the braces, a propeller shaft carried by the braces, and means for operating the propeller shaft from the pedal crankshaft, a rudder and a rudder shaft supported between the hulls, a steering arm on the rudder shaft, a crankarm on the steering post, a bell crank lever rockably mounted at its angle adjacent one of the hulls, a link operatively connecting the crankarm on the steering post to one of the arms of the bell crank lever, a steering rod arranged in close proximity to one of the hulls, and operatively connected to the other arm of the bell crank lever, the rear end of the steering rod having an angled portion extending toward the rudder, and means operatively connecting the rear end of the steering rod to the steering arm.
